Specification for Design.

Patented July 11, 1911.

Application filed August 29, 1910. Serial No. 579,603. Term of patent 14 years.

To all whom it may concern:

Be it known that I, GEORGE E. CURTISS, a citizen of the United States, residing at New Britain, in the county of Hartford and State of Connecticut, have invented a new, original, and ornamental Design for the Handle of a Fork, Spoon, or Similar Article, of which the following is a specification, reference being had to the accompanying drawing, forming part thereof.

Figures 1 and 2 are respectively obverse and reverse views of the handle of a fork, spoon or similar article. Fig. 3 is a sec-

tional perspective view of the obverse side of the handle on the line 3—3 of Fig. 1, and Fig. 4 is a sectional perspective view of the reverse side of the handle on the line 4—4 of Fig. 2.

I claim:—

The ornamental design for a handle of a fork, spoon, or similar article, as shown.

GEORGE E. CURTISS.
